(57) **CLAIM**

The ornamental design for a ladder with hinged rungs operable to collapse on multiple axes, as shown and described.

DESCRIPTION

FIG. 1 is a front view of a ladder with hinged rungs operable to collapse on multiple axes showing my design;

FIG. 2 a top view thereof;

FIG. 3 a bottom view thereof;

FIG. 4 a rear view thereof;

FIG. 5 a rear right perspective view thereof;

FIG. 6 a rear left perspective view thereof;

FIG. 7 a right view thereof; and,

FIG. 8 a left view thereof.
